UNITED STATES PATENT OFFICE.

JOHN F. SANDELL, OF CHICAGO, ILLINOIS.

INTERNAL-COMBUSTION ENGINE.

1,391,981.

Specification of Letters Patent. Patented Sept. 27, 1921.

Application filed October 25, 1919. Serial No. 333,222.

To all whom it may concern:

Be it known that I, JOHN F. SANDELL, a citizen of the United States, residing at Chicago, in the county of Cook and State of Illinois, have invented a new and useful Improvement in Internal-Combustion Engines, of which the following is a specification.

My invention relates to internal combustion engines, but is particularly adapted for use with internal combustion engines of the two-cycle type. It is fully described in the following specification and illustrated in the accompanying drawings, in which—

15 Figure 1 is a partial vertical section longitudinally of the cylinder. Fig. 2 is a similar view showing in detail a modified form of fuel governing mechanism. Fig. 3 is a view similar to Fig. 2 but showing part of 20 the governing mechanism in elevation. Fig. 4 is a side elevation taken on the line 4—4 of Fig. 3, and Fig. 5 is a partial section on the line 5—5 of Fig. 2.

I have illustrated an embodiment of my 25 invention in an internal combustion engine having a cylinder 10 in which is slidable a piston 11 into which is threaded a piston rod 12, the opposite end of which is connected to a cross-head 13, and this by means 30 of a cross-head pin 14 and a connecting rod 15 to any ordinary form of crank-shaft. The cylinder 10 is carried on the crank-case 16. Between the crank-case and the cylinder however, is interposed a circular flange 35 17, to which is integrally connected a hollow circular guide 18 having guide-ways 18^a at each side thereof, in which the cross-head 13 is slidable.

The upper end of the hollow guide 18 is 40 surmounted by a cap-member 19 which is preferably screwed thereon and which has a circular valve-seat 19^a which is concentrically located with respect to the piston rod 12. A valve 20 is made slidable on the 45 piston rod 12 and has metallic packing rings 21 therein, so as to provide an air-tight fit between the valve 20 and the piston rod. A collar 22 threaded into the upper portion of the valve 20 retains these rings in place, 50 while another collar 23 is threaded into the upper portion of the cap-member 19. This latter collar is spaced some distance above the valve, so as to allow a certain amount of

play between the valve 20 and its seat 19. The upper portion of the cap-member 19 has a series of transverse openings 19^b there-through, so that when the valve 19 is raised there is a direct passage formed, whereby air may pass from the interior of the hollow guide 18, into the interior of the piston. 60

Surrounding the hollow guide 18 is a circular chamber 24, which is closed at its lower end and communicates through the passage 25 and the fuel-mixing passage 26 with the inlet ports 27 at the bottom of the combustion chamber. Exhaust ports 28 are oppositely disposed to the inlet ports and these communicate with the exhaust passage 29. The opening of the passage 25 into the fuel mixing passage 26 is normally covered 70 by means of a clack-valve 30, which is hingedly mounted at 31 to a block 32 which is made adjustable back and forth by means of a screw 33, which is adjustable in a slot 34. A plunger 35 rests upon the upper portion of the clack-valve near its pivotal point, 75 and is pressed thereto by means of a spring 36. This plunger is slidable up and down in a pump-chamber which receives fuel through the fuel-supply pipe 38. This 80 pump is supplied by a ball-check valve 39 and forces fuel out through the spray nozzle 40, which is normally held on its seat by means of a spring 41. The throttle 42 is placed in the passage 25 and may be controlled either by hand or by means of a governor. The operation of this engine is as follows:

As the piston ascends, the valve 20 is raised due both to the partial vacuum produced in the space beneath the piston and to the friction of the valve 20 on the piston rod. Air will therefore be drawn in through the openings 19^b and as the piston again descends the valve 20 will seat due to gravity, 95 to the pressure from within and to the friction of the valve on the piston rod. This air is then forced gradually past the clack-valve 30. The valve 30 is normally held slightly raised by means of a spring 30^a, in 100 consequence of which as the piston descends and air begins to be compressed in the passage 25 some air will leak around the opening under the valve 30 without materially raising it, thereby filling the mixing chamber 26 with nearly pure air. 105

As the piston further descends the exhaust ports 28 will be uncovered first, and the burned charge will consequently begin passing into the exhaust passages 29 before the 5 inlet ports 29 are uncovered. As soon, however, as these inlet ports are uncovered the compressed air in the passages 24, 25 and 26 immediately rush in and the pure air previously mentioned in the passage 26 acts 10 as a scavenger for the burned gases in the cylinder. By this time, however, enough force is applied to the valve 30 that it is raised an appreciable amount, thereby actuating the plunger 35 and causing a charge 15 of fuel to be ejected past the valve 40. The height to which this valve will be raised will depend in a great measure upon the setting of the throttle 42. This charge is taken up by the on-rushing air which carries it 20 through the inlet ports 27 into the interior of the cylinder.

The amount of fuel fed may be adjusted by moving the block 32 back and forth by means of the adjustment of the screw 33 in 25 the slot 34. As this block is moved to the left a greater movement is accordingly provided between the center of the hinged pin 31 and the center of the plunger 35. As the piston again rises the inlet and then the 30 exhaust ports are closed and the check-valve 30 is returned to its seat by gravity and by the action of the spring 36.

In Figs. 2 to 5, I have shown a modified but preferred form of my invention. In this 35 the construction of the piston rod, valve 20, etc., are the same as those shown in Fig. 1, the principal difference being in the method of supplying fuel to the mixing chamber.

40 The extension 11^a of the piston engages a plunger 43 at the lowermost point of the piston stroke. This plunger is partially surrounded by a yoke 44 which is guided upon a part of the cylinder casting 10^a by 45 means of screws 45. The lower ends 44^a of the yoke 44 are inturned and tapered so as to form tapering shoulders beneath which are slidably mounted wedges 46. Each wedge carries at its free end a pin 47 which 50 engages a rocker arm 48 which is hingedly mounted at 49 to an extension 10^b of the cylinder casting 10^a. The rocker arm 48 is connected by means of a pin 50 and a push-rod 51 with a cam 52, which is carried by 55 the throttle 42^a.

The plunger 43 is part of a pump which receives liquid fuel through the intake pipe 53, past the inlet check-valve 54, and delivers it past the check-valves 55 and 56 60 to the spray nozzle 40, as in the form illustrated in Fig. 1. Air is supplied as before by means of the compression due to the action of the piston 11 which forces air around through the passages 25 and 26 to the combustion chamber of the engine. Owing to 65

the fact that the plunger 43 is not depressed by the action of the piston until after the inlet port 27 has been uncovered, the first air which is forced into the engine cylinder will contain little, if any, fuel, and as before will act as a scavenger for the exhaust gases of the previous charge. As the piston descends, however, the plunger 43 is depressed and a charge of fuel is sprayed into the mixing chamber 26, where it is picked 75 up by the in-rushing air and carried into the combustion chamber of the engine.

As the throttle is closed the cam 52 forces the rod 51 down, thereby causing the wedges 46 to be pushed farther under the yoke 44. 80 The yoke is therefore forced down against the action of the spring 44^a and the relative movement of the plunger 43 is accordingly restricted. As this movement is shortened the amount of fuel fed each time is accordingly lessened, so that by a proper adjustment of the parts the amount of fuel fed each time is accordingly proportioned to the amount of air which is allowed to pass the throttle 42^a. Upon each actuation of the 85 plunger 43 by the piston it is, of course, returned by the spring 43^a as far as is permitted by the yoke 44.

While I have shown and described but two embodiments of my invention, it will be understood that numerous modifications are possible. Changes therefore in the construction and arrangement may be made which do not depart from the spirit and scope of my invention as disclosed by the appended claims, in which it is my intention to claim all novelty inherent in my invention as broadly as is possible in view of the prior art.

What I claim as new and desire to secure 105 by Letters Patent is—

1. In an internal combustion engine, a cylinder, means for compressing air for said engine cylinder, a passage from said means to said cylinder, a throttle in said passage, a fuel nozzle in said passage between the throttle and cylinder, and means for ejecting fuel from said nozzle after part of the air in said passage has been passed into the cylinder.

2. In an internal combustion engine, means for compressing air for said engine cylinder, a passage from said means to said cylinder, a throttle in said passage, a fuel nozzle in said passage between the throttle and cylinder, and means for ejecting fuel from said nozzle after part of the air in said passage has passed into the cylinder, said latter means being under control of the throttle so that the fuel fed is proportional 115 to the throttle opening.

3. In an internal combustion engine, means for compressing air for said engine cylinder, a passage from said means to said cylinder, a throttle in said passage, a fuel 120

125

130

nozzle in said passage between the throttle and cylinder, and a pump plunger operable directly by the piston for ejecting fuel from said nozzle after part of the air in said passage has passed into the cylinder.

4. In an internal combustion engine, means for compressing air for said engine cylinder, a passage from said means to said cylinder, a throttle in said passage, a fuel nozzle in said passage between the throttle and cylinder, a pump plunger operable directly by the piston for ejecting fuel from said nozzle after part of the air in said passage has passed into the cylinder, and means

10 associated with the throttle for controlling the displacement of said pump plunger.

5. In an internal combustion engine, means for compressing air for said engine cylinder, a passage from said means to said cylinder, a valve in said passage, a fuel nozzle in said passage between said valve and cylinder, and means controlled by the

valve for controlling the amount of fuel fed by the nozzle.

6. In an internal combustion engine, 25 means for compressing air for said engine cylinder, a passage from said means to said cylinder, a throttle in said passage, a fuel nozzle in said passage between the throttle and cylinder, and a pump plunger operable 30 directly by the piston for ejecting fuel from said nozzle.

7. In an internal combustion engine, a cylinder, a piston therein having a piston rod secured to the piston, a tubular member 35 surrounding the piston rod and secured to the cylinder to form a chamber, an opening between said chamber and the interior of the tubular member and a valve for closing said opening, said piston at the bottom of its 40 stroke partially surrounding said tubular member.

JOHN F. SANDELL.
